UNITED STATES PATENT OFFICE.

MAX MAURAN, OF NIAGARA FALLS, NEW YORK, ASSIGNOR TO THE MATHIESON
ALKALI WORKS, INC., OF NEW YORK, N. Y., A CORPORATION OF VIRGINIA.

DRUM.

Application filed November 8, 1924. Serial No. 748,626.

This invention relates to a method of making drums, and more particularly drums for shipping chemicals which must be protected from the atmosphere, and also to a drum made according to this method which affords many advantages over the drums previously used.

Chemicals of various kinds, such, for instance, as hypochlorite of lime, commonly used for bleaching purposes, are shipped in metallic containers which are sealed so as to protect the contents from the atmosphere. These containers ordinarily are in the form of cylindrical drums made of thin sheet metal, and in one form the container consists of a tubular body portion with circular disc heads which are united to the body portion in any convenient manner, as, for instance, by double seaming. When these drums are used for export purposes the heads must be reinforced on account of the rough handling to which the drums are frequently subjected during transportation, and for this purpose one type of drum which has frequently been used consists of a tubular body which has disc heads closing either end of the body, and these heads are reinforced by wooden plates or heads which have been placed within the metal heads. The wooden head in the bottom is placed in position before the contents are introduced and is held there by means of nails driven through the side wall of the drum. The wooden head in the bottom is placed directly against the metal head and after being put in position the chemicals to be transported are introduced into the drum, then similar wooden and metal heads are used to close the other end of the drum. In order to seal the drum tightly it has been customary to solder over the heads of the nails which are used to hold the wooden heads in position. This type of drum, while satisfactory for some purposes, has numerous disadvantages. It is expensive to manufacture on account of the amount of manual labor which is involved in placing the wooden reinforcing heads in position and further manual labor is required in sealing the nail holes, as previously referred to. Furthermore, the wooden reinforcing heads lie within the container and it has been found that under certain conditions the wood inside the drum gets soggy and induces the rusting of the drum.

The present invention is intended to pro-

vide an improved form of drum which avoids the disadvantages of the previous construction, which is cheap to manufacture, and which has the necessary reinforcement, and also to provide a method of manufacturing such drums by which they may be constructed at a relatively low cost.

In the accompanying drawings that embodiment of the invention which is preferred, and also certain steps of the method by which such a drum is constructed, are illustrated.

In these drawings,

Fig. 1 is a longitudinal, sectional view of the improved type of drum, 70

Fig. 2 is a sectional view of a detail of the improved drum at one stage in the course of its manufacture,

Fig. 3 is a view similar to Fig. 2, but showing the completed operation, 75

Fig. 4 is a sectional view of a drum in slightly modified form,

Fig. 5 is a sectional view of a detail of the drum illustrated in Fig. 4, 80

Fig. 6 is a sectional view of a detail of a modified form of drum, and

Fig. 7 is a sectional view of a detail of another modified form of the drum.

In these drawings the drum is shown to consist of a body portion 6 which ordinarily is in the form of a metal cylinder. This body, in a drum which is frequently used for commercial purposes, is made of #22 Ga. sheet steel, black or galvanized, and usually the drum is in the form of a cylinder. The ends of the drum are closed by metal heads 7, these heads being made of the same material as the side wall of the drum. As shown in Fig. 3, the head 7 has an upstanding marginal flange 8 which fits within the end of the body and to secure the head in position so as to close the drum the edge of the flange 9 and the edge of the body 10 are turned outwardly and seamed together, as indicated generally at 11. With this arrangement the flange and the edge of the body portion form a chime, and as this chime is made up of several thicknesses of metal it is quite stiff and rigid.

As heretofore constructed, when the lower head has been placed in position a reinforcing head made of wood is placed within the drum, this wooden head having a diameter approximately equal to the inner diameter of the body of the drum, and the wooden

head is placed against the inner face of the lower head and then held in position by nails which are driven through the side wall. In order that the drum may be air tight, it is necessary to solder over the heads of the nails exposed on the outer face of the drum so as to prevent leakage through the nail holes. The other end of the drum is closed in a similar manner.

In making the present drum, however, a body portion 6 is first made in the usual way and the head 7 formed with the marginal flange. This flange has a considerable extent, as will be seen from Fig. 2, and a reinforcing head 12 is placed within the metal head, the edge of the wooden head lying closely against the metal flange. The reinforced metal head is then placed in position in the end of the drum with the flange 9 as shown in Fig. 2, extending for some distance beyond the edge of the body portion. This projecting portion of the flange and the portion of the edge of the body which extends beyond the face of the wooden head 12, are then seamed together, as shown in Fig. 3, and in this seaming operation a chime 11 is formed, a portion of which, as shown at 13, overlies the metal head. This overlying portion in the course of its formation, is forced into the rim of the wooden head and by its engagement therewith holds the latter against displacement. It will be seen from Fig. 3 that the chime formed in the manner described extends a sufficient distance into the rim of the wooden disc as to hold the latter firmly against displacement, and it is not necessary to make use of nails or any other anchoring devices in addition to the overlying portion of the chime. The drum so produced is sealed tightly but the reinforcing discs or heads are kept from contact with the contents of the drum and therefore provide the desired strengthening effect without any of the disadvantages of the older type of head which was within the interior of the drum.

In Figs. 4 and 5 there is shown a slightly modified form of construction in which the wooden head 7 is provided with a circumferential rabbet 14, this rabbet being formed in the edge of the outer face of the wooden head. With this type of construction the drum is made as before, the flange on the metal head being seamed over together with the edge of the body so as to form a chime 13, this chime entering the rabbet and thus locking the wooden head against displacement. It will be seen that in either type of construction the same advantages are gained. The reinforcing head of wood lies outside the metal head and therefore does not come in contact with the contents of the drum, and at the same time this head is held firmly in position without the use of securing devices which pass through the wall of the

drum. The same seaming operation by which the metal head is secured in place to close the end of the drum serves to secure the reinforcing head in place and thus the number of operations required for the manufacture of the drum is considerably reduced. Also, there is no danger of leakage such as would occur if the soldering around the nail heads, as required in the older type of drum, were omitted.

In Fig. 6 there is shown a still further modified form of construction which differs from those shown in Figs. 3 and 5 in that the wooden reinforcing head is held in position by a portion of the chime which overlies the face of the head, rather than by the engagement of the chime in a rabbet or by being forced into the edge of the head. In the construction illustrated in Fig. 6, the metal head is inserted a sufficient distance into the end of the drum so that when the reinforcing plate 12 is placed in position the flange 9 and the edge of the body 10 extend a slightly greater distance beyond the face of the plate than is the case in the constructions illustrated in Figs. 3 and 5. The edge of the body and the flange are again seamed together with the double seam construction, and the interlocked portions of the flange and body are then turned inwardly, as indicated at 15, so as to overlie the edge of the reinforcing plate. This overlying portion of the seam serves to lock the plate in position against dislodgment. As before, the chime has a slightly less internal diameter across the inner edge of the seam than the diameter of the reinforcing head, so that when the head is placed in position and the flange and body seamed together, the head cannot be accidentally removed.

In Fig. 7 there is shown a somewhat different construction, in which a reinforcing plate is again made use of, this plate lying outside the face of the metal head and being protected by the projecting portion of the chime 11. After the wooden plate is placed in position it is secured by means of nails 16 which are driven through the side wall of the body and the flange at spaced points around the head. The nails provide anchoring means by which the head is held against displacement, but since the plate is positioned outside of the body the passage of the nails through the side wall of the body does not break the seal and consequently it is not necessary to solder the heads of these nails to prevent the admission of the atmosphere to the contents of the drum. With this construction, as before, the edge of the chime projects slightly beyond the face of the wooden plate and as this edge is formed of the interlocked portions of the flange and the edge of the body, it has considerable stiffness so that the head is protected against injury.

I claim:

1. A drum comprising the combination of a metal body portion, a metal head having a marginal flange, a wood reinforcing plate 5 of a thickness less than the width of the marginal flange lying on the outer surface of the head, the portion of the flange which extends beyond the plate being seamed with the edge of the body portion to form a chime 10 the outer edge of which is substantially flush with the outer face of the reinforcing plate, this chime being forced into the edge of the reinforcing plate to compress the wood whereby the plate is held against displacement.

2. A drum which comprises the combination of a metal body, a metal head therefor having a diameter substantially the same

as the inner diameter of the body and placed within the end of the body, a peripheral flange on the head having a portion lying in contact with the inner face of the body, the edge of the flange being folded outwardly over the edge of the body and the two edges crimped together to form a chime 20 lying beyond the face of the head, this chime having an inner diameter less than that of the body, and a wooden plate of substantially the same diameter as the head disposed on the latter and held in place by the inner surface of the chime which enters the edge of the plate, the plate having a thickness such that no portion of it projects outwardly beyond the edge of the chime.

In testimony whereof I affix my signature.
MAX MAURAN.
